(57) **CLAIM**

The ornamental design for an LED ceiling lamp, as shown and described.

DESCRIPTION

FIG. 1 is a first perspective view of an LED ceiling lamp showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the LED ceiling lamp in which the design is embodied that form no part of the claimed design.
